DESIGN FOR A RING MOUNTING OR SIMILAR ARTICLE OF JEWELRY

Paul E. Hanson, Seattle, Wash.

Application May 4, 1937, Serial No. 69,160

Term of patent 7 years

To all whom it may concern:

Be it known that I, Paul E. Hanson, a citizen of the United States of America, residing at Seattle, county of King, and State of Washington, have invented a new, original, and ornamental Design for a Ring Mounting or Similar Article of Jewelry, of which the following is a specification, reference being had to the accompanying drawing, forming a part thereof, wherein:

Figure 1 is a view in side elevation of a ring mounting or similar article of jewelry, showing my new design.

Figure 2 is a top plan view.

Figure 3 is an end elevation.

I claim:

The ornamental design for a ring mounting or similar article of jewelry, as shown.

PAUL E. HANSON.
